CLAIM

I claim the ornamental design for a self-contained accessory for the removal of hair, particularly for feminine use, as shown and described.

DESCRIPTION

FIG. 1 is a front elevational view of a self-contained accessory for the removal of hair, particularly for feminine use, showing my new design.

FIG. 2 is a right-side elevational view thereof.

FIG. 3 is a rear elevational view thereof.

FIG. 4 is a left-side elevational view thereof.

FIG. 5 is a top plan view thereof, looking down on the drawstring.

FIG. 6 is a bottom plan view thereof.

FIG. 7 is a front view similar to FIG. 1, showing the design in an alternate configuration with the ring lowered and the encased soap bar reduced in size;

FIG. 8 is a partial pictorial view, showing how the accessory is applied by a lady to her leg prior to shaving excess hair therefrom; and,

FIG. 9 is a further pictorial view, showing the accessory being suspended by its draw string from a shower head. The variations herein in the outlines of the mesh bag and string are due to the flexible nature of the design.

The broken lines showing the human form, soap bubbles, shower head and other environmental surfaces are for illustrative purposes only and form no part of the claimed design.

1 Claim, 2 Drawing Sheets
